MASON'S CORNER GAUGE

Stanley V. Wells, Washington, D. C.

Application July 13, 1955, Serial No. 521,820

3 Claims. (Cl. 33—85)

The present invention relates to corner-gauges useful by masons in the erection of the corners of buildings.

It is common practice in erecting walls of a building or like structure with brick, stone and similar block-form members to build or "raise" the corners of angularly disposed walls of the structure before the main or intermediate wall portions are "laid" or erected; and, after the corners have been built-up to a certain number of courses, the intermediate portion of the wall is built-up progressively and tied in bonded relation with the corner portions, the corners always being progressively "raised" ahead of the main portion of the wall until the top is reached.

Many proposals have been made heretofore to provide a mason's corner-gauge to replace the use of "spirit level" for plumbing and leveling the brick or blocks forming the corner of walls, but most of these are cumbersome, complicated or otherwise inefficient for the purpose, particularly in use with skeletonized structures as they require frequent manipulation, rearrangement and/or adjustment as the corner is progressively erected, and, if relied upon too closely, produce an inaccurate or out-of-plumb corner.

The object of the invention is to provide an extremely simple and inexpensive mason's corner gauge that may be set in place quickly on skeletonized steel-frame or concrete structures and with great ease over devices now in use, and can be easily adjusted in position to heights from one story to as many stories as may be desired to meet present construction practices with great advantages to the bricklayer or mason and, after once positioned, may remain in place until the full height of the corner is completed.

Other objects of the invention will be apparent as this specification proceeds, and the invention resides in the novel construction of and the arrangement of its few and simple parts.

A full and complete understanding of the present invention may be had from the following description and the accompanying drawings, which show the invention in the form it is now manufactured and used; and the novel features of the invention are pointed out in the appended claims.

In the drawings:

Figure 1 is a top view of the invention;

Figure 2 is a side elevation of the invention;

Figure 3 is a fragmentary sectional view of the lower end portion of the adjustable screw for holding and tensioning the gauge-line;

Figure 4 is a perspective view showing the corner-gauge applied in use in connection with a skeletonized concrete or steel frame of skeletonized building structure;

Figure 5 is a top plan view of the gauge-line corner anchor plate showing its use with a cord-type gauge-line;

Figure 6 is a front edge view of the anchor plate shown in Figure 5;

Figure 7 is a view of the anchor plate similar to Figure 1 but showing the manner of attaching a wire-type gauge-line thereto; and

2

Figure 8 is a fragmentary elevation illustrating the manner of attaching a wire-type gauge-line to the tensioning screw and the anchor plate.

Referring in detail to the drawings, in which like characters of reference refer to similar and like parts throughout the several views, the corner-gauge of the present invention comprises an arm 10, preferably of rigid metal-bar stock having its end portions *a* and *b* offset and extending in spaced parallel planes, respectively, and its connecting intermediate portion *c* preferably extending normal to its end portions, thus providing an elevated forward projecting gauge-line supporting arm *a* and a rearwardly projecting base or foot *b*. The end of arm *a* has a threaded opening 10a therethrough near its outer extremity and whose axis is normal to the plane of said arm *a*. The other foot portion *b* of the arm 10 may be of any desired length to rest upon a horizontal support or floor *s* of the building structure *B* and fixedly held in position in any suitable manner, such, for instance, by applying weighted material *w* thereupon (such as bags of sand and the like), placed as indicated in Figure 4 or by wedging the ends of a length of material (such as a "2 x 4," not shown) between its inner end *b* and the floor above, as is common practice in scaffolding and other connections. However, it is preferred to have the foot portion *b* of the arm 10 relatively short (i. e. about 18 to 24 inches long) and to provide it with a pivoted rear extension 11 having a laterally projecting threaded stud 12 at its inner end which slidably extends through an elongated slot 10b in and longitudinally of the end portion *b* of the arm 10, a wing nut 13 being threaded on the outer end of stud 12 to bind the parts together in adjusted position.

A threaded rod 14 is threaded in the opening 10a of the arm 10, and has a winged upper end 14a by which it may be adjusted relative to the end *a* of the arm 10. The other or lower end of the rod 14 is formed with an axially disposed bore or passage 15 therein, which extends through and from the lower extremity of the rod 14 upwardly or inwardly for a distance where, as at 15a, it is directed laterally of the rod to open through the side surface thereof.

A gauge-line 16, preferably of nylon cord or of a steel wire, has its upper end portion extending through the passage 15, as shown in Figure 3, with its extremity projecting from the passage opening 15a where it may be releasably clamped to the rod 14 by a wooden wedge plug 17 or, when the gauge is of wire, by a nut 18 threaded on the rod 14 as shown in Fig. 8. The other or lower end of the gauge-line 16 is held in position by a plate-form anchor member 19 insertable in a mortared joint at the corner of the walls.

The anchor plate 19 is provided with an open-ended elongated slot 19a extending from one edge of the plate inwardly for a distance and with a notch or shorter slot 19b extending substantially right-angles to and substantially aligned with the inner end of the slot 19a. The lower end portion of the gauge-line 16 is inserted in the slot 19a to lie against the inner end of the slot; and a sufficient length of the lower end of the line 16 is wound transversely about the anchor 19 with portions of the wound convolutions lying in the notch 19b to keep the portion of line in slot 19a in contact with its rear or inner end particularly when the line 16 is of cord as shown in Figs. 5 and 6. When the line 16 is of wire, an enlargement 20 is provided on its lower extremity in the form of a collar, into which said extremity is inserted and held fast thereto by a set-screw 20a, the lower end of the line being inserted in the slot 19a and its lower extremity engaging in the notch 19b with said collar 20 contacting the upper surface of the plate 19, as shown in Figs. 7 and 8. Jam nuts 21 may be provided on the rod 14 to bind the

rod in its adjusted positions to maintain the line 16 taut.

The gauge-line 16 is to be provided with marking 22, which may be of contrasting colors, spaced apart a distance equal to each course of brick or block, thus eliminating the manual marking of courses by movable cord lines and the frequent inspection by the mason to maintain his proper spacing of courses.

In the use of the present invention, the mason will have established the outside corner point *p* for the corner of two angularly disposed walls *y* and, as is the custom, will have laid several courses of brick or the like *z* in the usual manner at the corner. The slotted anchor plate 19 is then inserted into a horizontal mortared joint with the open end of the slot 19a outermost and with the inner end of the slot 19a directly at and aligned with the established corner *p*, thereby intersecting the vertical line of said corner. The supporting arm 10 is then carried to any upper floor, roof or beam *s* of the skeletonized structure *B* and placed adjacent to the corner, to be erected, with its foot portion *b* resting thereupon and counterweighed in any suitable manner, or as above described, and with the lower end of the rod 14 pointing downwardly and overlying the corner point *p*. Should the building frame structure have a corner column or post *k*, as is now customary, the foot extension 11 will be employed and, as generally indicated in Figure 4, by pivoting the arm 10 and the extension 11 about the stud 12 and/or sliding the stud 12 in the slot 10b, the passage 15 in the rod 14 can be placed in proper vertical coincident alignment with the corner point *p*. This may be quickly and easily accomplished by clamping the upper end of the gauge-line 16 of proper length in the passage 15 of the rod 14, as above described, and attaching a plumb-bob on the lower end of the line 16 to plumb the rod 14 with the corner point *p*; then removing the bob and inserting the lower end of the line 16 in the slot 19a, in the manners previously described, and then finally adjusting the rod 14, by means of its winged-end 14a, to place the gauge-line 16 under sufficient tension to make and maintain it taut, so that the line 16 will lie coincident with the wall corner and act as a gauge to which the corner edges of subsequently laid brick or the like will contact. Another manner for setting the arm 10 and plumb the line 16 is, after the anchor plate 19 has been set, to insert the lower end of the line 16 into its slot 19a (as above described), then fasten the line 16 to the rod 14, as above described, and then plumb the taut line with a surveyor's transit instrument or with a spirit level by shifting the arm 10 as may be required to bring the gauge-line 16 coincident with the corner edge of the walls *y*, which has been initially started or erected, as shown in Figure 4.

It will thus be seen that the gauge-line needs to have only one setting for a building, or such portion thereof as may be desired, and, once in position and maintained taut, by rotatably adjusting the rod 14, it will remain in proper gauging position until the entire corner has been erected, thereby saving the time of the mason in adjusting guides, the frequent repeated use of spirit levels, straight-edges and the like to maintain a plumb corner, thus giving the mason more time for the actual laying of brick, stone or block.

From the above, it is manifest that the objects of the invention are attained by the device herein shown and described, and that the device is simple, economical, easy to use and positive in operation for its use.

Having described the present invention and the manner in which it is to be performed, it is to be understood that the invention is not to be limited to the exact form of construction herein shown and described, as it is susceptible to various modifications which fall within the scope of the appended claims.

That which is claimed, as new and to be secured by Letters Patent, is:

1. An adjustable supporting and tensioning device for a vertical corner gauge-line used in erecting masonry structures, said device comprising a rigid bar-shaped member having its opposite end portions offset to lie in spaced planes and its intermediate portion angularly disposed between said planes, one of said end portions forming a gauge-line supporting arm and the other forming a supporting base for said device, an elongated rod threadedly supported in and substantially normal to the plane of said gauge-line supporting arm, means for threadedly adjusting said rod relative to said arm, and means at one end of said rod for releasably attaching a gauge-line axially thereto.

2. An adjustable supporting and tensioning device for a vertical corner gauge-line used in erecting masonry structures, said device comprising a rigid bar-shaped member having its opposite end portions offset to lie in spaced planes and its intermediate portion angularly disposed between said planes, one of said end portions forming a gauge-line supporting arm and the other forming a supporting base for said device, an elongated rod threadedly supported in and substantially normal to the plane of said gauge-line supporting arm, means for threadedly adjusting said rod relative to said arm, means for attaching a gauge-line to one end of said rod, and an extension member at the outer end of said base portion of said device and having a laterally pivoted and relatively longitudinal sliding connection with said base and adapted to be fixedly secured to a supporting surface.

3. The subject matter of claim 1 wherein there is an anchor member to which the other end of the gauge line is attachable, said member having an open-ended slot therein to receive said gauge line and a notched edge-portion laterally disposed with respect to said slot.
